UNITED STATES PATENT OFFICE.

CHARLES HART, OF OAKLAND, CALIFORNIA, ASSIGNOR TO THE HART HEATER COMPANY, A CORPORATION OF CALIFORNIA.

BURNER FOR WATER-HEATERS.

978,123.

Specification of Letters Patent.

Patented Dec. 6, 1910.

Application filed November 30, 1909. Serial No. 530,601.

To all whom it may concern:

Be it known that I, CHARLES HART, a citizen of the United States, residing at Oakland, in the county of Alameda and 5 State of California, have invented certain new and useful Improvements in Burners for Water-Heaters, of which the following is a specification, reference being had thereto in the accompanying drawing.

10 This invention relates to burners for water heaters and the principal object of the same is to provide a burner for use in connection with a plurality of water coils so that the flames may be projected into the 15 coils to thoroughly heat all parts of the same and also to prevent condensation on the convolutions of the coils and thereby prevent the usual drippage from water coils which interferes with the proper combustion 20 of the fuel.

In carrying out the objects of the invention generally stated above it will be understood, of course, that the essential features thereof are necessarily susceptible of changes 25 in details and structural arrangements, one preferred and practical embodiment of which is shown in the accompanying drawings, wherein:—

Figure 1 is a view in elevation of a water 30 heater, with the casing in vertical section, showing the improved burner. Fig. 2 is a top plan view of the burners, the water coils that are heated thereby being indicated by dotted lines. Fig. 3 is a fragmentary 35 vertical sectional view of the fuel supply pipe showing the air supply therefor and also means for mixing the gas and air.

The water heater shown in the accompanying drawings, in so far as the arrangement of casings and water coils, and the water supply is concerned, is the same as that shown in the pending application Serial No. 496,451, filed May 17, 1909, and it is the aim of the present invention to provide 40 a burner especially adapted for heating coils that are used in connection with the type of heater shown in said application.

Referring to said accompanying drawings by numerals, 1 designates the outer casing, 50 2 the inner casing or boiler in which the four coils 3 are vertically arranged in radiating relation to a common center. The coils are supplied with water from a single supply pipe 4, and discharge into a single

pipe 5 that extends through the reduced 55 upper or flue end 6 of the boiler 2.

The open lower end of the boiler 2 is closed by the plate 7 that has a central opening 8 through which the supply pipe 4 projects, said central opening 8 being surrounded by inclined openings 9 that are arranged in radiating relation to said central opening.

The burner comprises the spouts 10, which project through the inclined openings 9 of the plate 7 and have their discharge ends 65 arranged so that one will be directly beneath each coil 3. Each spout is equipped with a collar 11 which support the plate 7. The lower ends of said spouts meet below the heater and are joined to a fuel supply pipe 70 12 that has a slotted section 13 through which air is fed to the gas or other fuel, and at a point above said slotted section, the pipe 12 is provided with transverse bars 14—15, arranged in crossing relation which 75 serve as mixer for the air and gas. The pipe 12 is in communication with a source of fuel supply, not shown, and is equipped with a controlling valve 16.

It will be seen from the foregoing that the 80 burner spouts 10 are held in position to cause them to direct their flame into and through the coils 3 so that said coils will be thoroughly heated at all points and thereby prevent condensation on the coils as the vapor 85 will be carried off through the flue end 6 of the boiler 2.

What I claim as my invention is:—

1. In an apparatus of the character described, a casing having openings in its bottom, and a burner consisting of a fuel supply pipe with diagonal branched ends projecting through the openings in the bottom of the casing, and having vertical open end portions located at spaced distances apart 95 from each other.

2. In an apparatus of the character described, a casing having an elevated closed bottom with a group of apertures arranged about the center of the bottom, a fuel supply 100 pipe having at its end a plurality of diagonal pipes united at one end with the fuel supply pipe and projecting through the apertures in the bottom of the casing and formed with vertical open ends, and means 105 located in the fuel supply pipe for feeding air thereto.

3. In an apparatus of the character de-

scribed, a casing having an elevated closed bottom with a group of apertures arranged about the center of the bottom, a fuel supply pipe having at its end a plurality of 5 diagonal pipes united at one end with the fuel supply pipe and projecting through the apertures in the bottom of the casing and formed with vertical open ends, means located in the fuel supply pipe for feeding air thereto

and a pair of cross bars located in the fuel 10 supply pipe adjacent to the air and gas mixing portion of the pipe.

In testimony whereof I hereunto affix my signature in presence of two witnesses.

CHARLES HART.
